Primary Examiner — April Rivas*Assistant Examiner* — Jillian Mazzola(74) Attorney, Agent, or Firm — Esplin & Associates, PC(57) CLAIM

The ornamental design for a shorts having contrasting regions, as shown and described.

DESCRIPTION

FIG. 1 is a front view of an embodiment of a shorts having contrasting regions, showing the new design; and

FIG. 2 is a rear view of the embodiment of FIG. 1.

FIG. 3 is a front view of another embodiment of the new design; and,

FIG. 4 is a rear view of the embodiment of FIG. 3.

The broken lines show portions of the article that form no part of the claimed design.

The contrasts in shading (illustrated by cross-hatching or line pattern, where appropriate) in FIGS. 1-6 represent contrast in appearance only, and do not represent any particular color, material, texture, or finish, with like-shading representing like-appearance within an embodiment.
